MECHANISM FOR EFFECTING NORMAL
AND REVERSE PLATING

John Lawson and Robert H. Lawson, Pawtucket,
R. I., assignors to Hemphill Company, Central
Falls, R. I., a corporation of Massachusetts

Application January 9, 1929, Serial No. 331,192

1 Claim. (Cl. 66—36)

This invention relates to mechanism for and process of effecting normal and reverse plating, the normal plating being herein disclosed as effected by needle deflection and the reverse plating being herein disclosed effected through the cooperation of sinker or like instrumentalities.

In order that the principle of the invention may be readily understood, we have disclosed in the accompanying drawings a single embodiment of means for practicing the invention.

In said drawings,—

Fig. 1 is a plan view of the sinker or web holder bed ring and showing in horizontal section the cams of the sinker cam ring, the top plate of said ring being removed;

Fig. 2 is a vertical central section upon the line 2—2 of Fig. 1 and looking in the direction of the arrows on said figure;

Fig. 3 is a detail in vertical section upon an enlarged scale on the line 3—3 of Fig. 1, and showing one of the several sinkers or like instrumentalities and the adjacent needle at a period in the operation somewhat prior to the casting off point, in the effecting of the reverse plating;

Fig. 4 is a view similar to Fig. 3, on the line 4—4 of Fig. 1, but representing the position of the parts at substantially the casting off point in reverse plating;

Fig. 5 is a view similar to Fig. 4 but representing the relative position of a needle and a sinker slightly prior to the deflection of said needle to effect regular plating; and

Fig. 6 is a view similar to Fig. 5 but representing the continuation of the movement for normal plating, about to be initiated in Fig. 5.

In accordance with our invention, we effect normal plating by slight, so-called, deflected movement of selected or predetermined needles transversely of the needle series and we effect reverse plating by cooperative movement of sinkers or like special instrumentalities without deflective needle movement. More broadly stated, we feed two yarns in a plating relation and we effect both normal plating and reverse plating, one of said types of plating being effected through needle deflection and the other type of plating being effected through the cooperation of sinkers or like special instrumentalities, but our invention is not limited to normal plating as effected by needle deflection, and reverse plating as effected by sinker cooperation because within the broad scope and purpose of our invention both normal and reverse plating may be otherwise effected than as herein shown. Herein we

have chosen to disclose the normal plating as effected by needle movement and that is the preferred manner of operation.

Our invention may be applied to any type of independent needle knitting machine, but we have represented the same as applied to a circular hosiery knitting machine of the latch needle type and have selected for illustration a Banner knitting machine without, however, limiting ourselves thereto.

The Banner machine to which our invention is here disclosed as applied is of the general type shown in the U. S. patent to Hemphill, No. 933,443, and shown also in U. S. patent to Robert H. Lawson, Reissue No. 16,584, April 5, 1927.

The machine is provided with needle cylinder 1 that may be of the usual construction but if desired the upper part of the needle grooves 2 may be sufficiently inwardly enlarged or deepened to permit sufficient inward movement of the needles. The needles are represented at 3 and while within the scope of the invention they may be of any type, they are preferably provided with hooks 4 and latches 5. The needle cylinder is desirably of the revolving type, though obviously the invention is not limited in this respect. We may provide a slight bend in the needle stems as indicated in the co-pending application of Lawson and Cloutier, Serial No. 184,576 filed April 18, 1927, so as to render the needles sufficiently springy for the purpose intended.

The web holder bed ring is indicated at 6 and the cap or cam ring is indicated at 7. The sinkers or web holders may be and desirably all are of a special type, though within the scope and purpose of our invention some of the sinkers may be of a usual type, as, for example, if normal plating is always to occur therewith. As stated, preferably and as herein indicated, all the sinkers are of special type and we have chosen to represent that special type shown in Figs. 2 to 6 inclusive. Therein the body of the sinkers is represented at 8, the lower nib at 9, the upper nib at 10, the throat at 11, the base portion of the sinker at 12, and the upstanding butt at 13. The butts 13 may in the simplest form of the invention be of all the same length, but different lengths may be employed upon different sinkers when employing different cams to act upon different sinkers. In the disclosed embodiment of the invention, however, the butts 13 are intended to be acted upon by the regular cam as indicated at 14 in Fig. 1 for effecting the casting off and therefore all of the butts may be of the same length. Preferably we employ a guide or

holding ring 15, which is mounted upon the extreme top of the needle cylinder 1, and is provided with an annular recess 16 which receives the inner ends 17 of the base portion of the sinkers as well as a needle deflecting instrumentality 18 to be hereinafter referred to. Said ring 15 is desirably not provided with radial recesses, but instead the annular recess 16 is circumferentially continuous, and serves not only to guide 10 the inner ends of the sinkers 8, but also the inner ends of the needle deflecting instrumentalities 18.

Each sinker or each special sinker 8 is provided with an inclined outer edge 19 down which one or it may be both of the yarns move in effecting reverse plating in a manner disclosed in Figs. 9 and 10 of our Canadian Patent No. 275,905, dated November 29, 1927. Desirably both of the threads pass down the rear edge 19 in the manner fully described in that patent.

20 The sinker cam ring, as shown most clearly in Fig. 1, is provided with an inner pathway 20 formed between an inner circumferential cam formation 21 having a cam 21' and an intermediate circumferential cam formation 22. 25 There are also provided an intermediate cam pathway 23 formed between the circumferentially extending cam formation 22 and an outer cam formation 24 that extends only part way about the sinker head, and also an outer pathway 24' which is outside of the cam formation 24 where the same exists, and extends about the entire circumference of the sinker cam ring. The intermediate cam formation 22 is provided with the incline 14 already referred to and the knitting point is indicated by the shoulder 25. The butts 13 of the sinkers are all received within the said circumferential pathway 20.

20 The needle deflecting instrumentalities 18 are preferably in number equal to the needles 3, being one for each needle. Desirably they respectively underlie the sinkers 12 as indicated in Figs. 2 to 6 and they have laterally bent inner ends 26, which, when they engage the needles, deflect the same very slightly outwardly as indicated in Fig. 6, so as to insure the effecting of normal plating. In order to move the said instrumentalities in and out, they are provided with butts 27 which at different stages of the operation of the machine travel in the outer pathway 24'.

As shown in Fig. 3, the sinkers 8 receive their reverse plating movements not through the agency of a cam formation acting upon the butts 13, but through the agency of the needle deflecting instrumentalities 18. To that end said needle deflecting instrumentalities are provided

each with a shoulder 28 which at the proper time impacts upon the end 29 of its sinker 8 and so moves the same inwardly as indicated in Fig. 3. At such time the butt 27 of the needle deflecting instrumentality 18 in question travels in the intermediate groove 23. Viewing Fig. 1 it will be observed that when the needle deflecting instrumentalities 18 travel along the intermediate groove 23 the shoulders 28 through their impact with the ends 29 of the sinkers 8 that effect reverse plating so move said sinkers inwardly that the two yarns are reversed in position as they move down the inclined sloping edge 19 and the stitch which is thus reversed is cast off at or near the lower end of said inclined edge 19. At other times the said butts 27 travel in the outer pathway 24' and the cam formation of that pathway is such that at the proper time the same causes the inner bent end 26 of the instrumentality 18 to engage the back of the stem of the needle as represented in Fig. 6 and move the needle very slightly outward but sufficiently to change from reverse plating to normal plating. When reverse plating is to be resumed, the proper sinkers 8 are moved inwardly in the special manner described so as to cause one or both of the threads to pass down the back of the sinkers.

The two threads are fed in a plating relation in a manner not necessary fully to describe, but desirably that disclosed in the patent to Robert H. Lawson, Reissue No. 16,584.

Having thus described one illustrative embodiment of the invention, and the best mode known to us for carrying out the process of the invention, it is to be understood that although specific terms are employed, they are used in a generic and descriptive sense and not for purposes of limitation.

We claim:

In a circular, independent needle knitting machine wherein two yarns are fed in a plating relation, a needle cylinder having at the upper end thereof a guide ring having a circumferential recess, a circular series of needles, a series of special sinker like instrumentalities for all the needles respectively, and a series of needle deflecting instrumentalities for all the needles respectively, the inner ends of said sinkers and needle deflecting instrumentalities being received in operation in said recess, and means for manipulating said sinkers and said needle deflecting instrumentalities in timed relation with the needles, so as to effect both reverse and normal plating.

JOHN LAWSON.
ROBERT H. LAWSON.
